PAPER ROLL HOLDER

James C. Andis, Rte. 1, Science Hill, Ky. 42553

Filed Jan. 17, 1969, Ser. No. 15,401

Term of patent 14 years

Int. Cl. D6—01

U.S. Cl. D52—2

Fig. 1

Fig. 2

Fig. 5

Fig. 3

Fig. 4

FIG. 1 is a top plan view of a paper roll holder showing my new design;

FIG. 2 is a front elevational view thereof;

FIG. 3 is a bottom plan view thereof;

FIG. 4 is a rear elevational view thereof; and

FIG. 5 is an elevational view taken from one side thereof, the opposite side being a mirror image of the side shown.

The side opposite from that shown in FIG. 5 is a mirror image thereof.

I claim:

The ornamental design for a paper roll holder, as shown and described.
